UNITED STATES PATENT OFFICE.

HERON SPARHAWK LANGFORD, OF ANN ARBOR, MICHIGAN, ASSIGNOR TO ANN ARBOR MACHINE CO., OF ANN ARBOR, MICHIGAN, A CORPORATION OF MICHIGAN.

CUTTER-WHEEL FOR ENSILAGE-CUTTERS.

1,249,426.

Patented Dec. 11, 1917.

Application filed September 13, 1916. Serial No. 119,960.

To all whom it may concern:

Be it known that I, HERON SPARHAWK LANGFORD, a citizen of the United States of America, residing at Ann Arbor, in the 5 county of Washtenaw and State of Michigan, have invented certain new and useful Improvements in Cutter-Wheels for Ensilage-Cutters, of which the following is a specification, reference being had therein to 10 the accompanying drawings.

This invention relates to fan wheels for silo fillers or other ensilage cutters, although the invention in its broader aspects is not limited to the particular use mentioned.

15 Among the objects of the invention are to provide a construction in which the cutting elements are mounted at one side of the spider frame and a rotating disk upon the opposite side of the spider frame with co- 20 operating fan blades or the like located in a plane between the plane of the cutting elements and the plane of the disk; to provide a construction in which the cut material that passes between the knife blades is prevented 25 from hitting against a stationary or dead wall, there being preferably a rotating disk member associated with the cutting elements and the fan blades.

The invention also resides in such other 30 features of construction and arrangements and combinations of parts as will more fully hereinafter appear.

In the drawings:

Figure 1 is a side elevational view of a 35 fan wheel embodying my invention.

Fig. 2 is an end elevation of the parts shown in Fig. 1, with part of the housing shown in section.

In detail A designates the rotating shaft 40 upon which is mounted the skeleton frame or spider B. The latter has a plurality of main arms such as C, C' and C''. Each of the arms carries a knife blade or cutting member D and the arms are so spaced from 45 each other as to provide openings E through which the material to be cut is fed, the fan wheel being somewhat similar to what is known as the open type of wheel.

In the present construction the fan wheel 50 is not in a strict sense of the word a "wheel" since the periphery is entirely omitted. The necessary strength for the wheel is however maintained by the employment of a strengthening header or reinforcing disk F and the 55 novel arrangement wherein the parts are to

be tied or secured together as to strengthen each the other. Thus in addition to carrying the knife blades D, each of the arms of the spider frame has one or more bearing portions to which are secured the fan elements. In the particular construction shown, each of the spider arms has provision for carrying two fan elements. The fan elements G are preferably formed separate from the spider and are secured to suitable bearing portions thereon by rivets H or other securing members. Also each of the fan elements is provided with a removable tip G' whereby any particular fan tip can be replaced at very slight cost and without affecting the balance of the wheel.

It will be noticed that the fan elements are positioned intermediate the plane of the knife blades and the plane of the disk or header F, and being riveted to both the 75 spider and the disk, they form in effect a truss reinforcement between these parts. In addition to strengthening the spider frame the disk or header F acts as an abutment wall against which the cut material strikes. 80 This materially reduces the friction since the cut material is prevented from striking against the stationary or dead wall of the housing J. By making the disk of a size to extend to the outer edge of the fan elements, all danger of the material catching or binding between the housing and the moving fan wheel is avoided and all danger of 85 obstruction of the material and friction between the material and the mechanism substantially eliminated, but on the contrary 90 providing a surface that is rotating in the direction in which the material is to be thrown, thus aids in the advancement of the material through the casing. The disk also 95 provides a safeguard from getting into the operating parts from the pulley side of the wheel and avoids the necessity of employing gratings or other separate guard members.

A further advantage is derived from the 100 fact that in my improved wheel the mounting for the fan elements is such that a greater number of the fan tips than cutting elements can be employed. Thus in the construction shown in the drawings, there are 105 three knife blades and six fan elements although the invention is not limited to the particular number or proportion stated. Also while I have shown the knife blades and fan elements carried by the spider and 110

the disk employed as a strengthening header, the invention is not necessarily limited to this particular arrangement, as a separate moving disk independent of the other elements might be employed to obtain some of the advantages above enumerated, and other changes in the construction and arrangement of parts could be made within the scope of my invention.

10 What I claim as my invention is:

A cutter wheel for ensilage cutters comprising a rotating spider having spaced arms, cutting elements carried by said spider and arranged so that the cut material passes

through the spaces between said arms, and a substantially closed disk member rotating in the same direction as the spider and positioned at one side of said spider and against which disk member the cut material strikes, said cutting elements and disk member being located in spaced-apart planes, and fan elements for throwing the cut material, said fan elements being carried by said spider and located in a plane positioned intermediate the planes of the cutting elements and disk.

In testimony whereof I affix my signature.

THERON SPARHAWK LANGFORD.
